UNITED STATES PATENT OFFICE.

ALFRED GEORGE PILBROW, OF CHICAGO, ILLINOIS.

PASS BOOK FOR BANKS.

Application filed May 31, 1927. Serial No. 195,169.

The invention relates to pass-books of the type used for savings bank accounts.

It is now common practice to provide these pass-books with an outer leaf, along 5 one of the side margins of which there is left a space for the number of the account and the insertion of the depositor's name subjoined to which is the caption and columns for the entry of the date of a transaction, 10 the deposit, and interest credits, the withdrawals, and the balances. Inside of this outer leaf are leaves with similar columns and titles, but which are shorter than the leaf containing the caption and depositor's 15 name, so that during the making of entries on the subsequent pages, the teller can observe the name of the depositor and the number of the account. The cost of manufacturing these books is increased by the 20 additional work involved in placement of the short leaves in correct position on the outer leaf, preparatory to binding them together. This added cost involves a considerable added expense on the part of the 25 bank which furnishes these pass-books to the depositor without charge.

One object of the invention is to provide an improved pass-book which can be produced at a lower cost by eliminating the 30 necessity of care and hand-work in binding the short leaves between the leaf containing the title and the depositor's name.

Another object of the invention is to provide a book of this type in which location by 35 the teller of the page containing the last entry will be facilitated. A still further object of the invention is to provide in these books an additional space for advertising matter.

40 The invention consists in the several novel features hereinafter set forth and more particularly defined by claims at the conclusion hereof.

In the drawings: Fig. 1 is a perspective 45 of the book. Fig. 2 is a plan of the book opened at the title page. Fig. 3 is a similar view opened at one of the succeeding pages. Fig. 4 is an end view with the leaves separated and with the margins of some of the 50 intermediate pages torn off after they have been filled.

The invention is exemplified in a book comprising a cover α of any suitable material, an outer sheet δ , and a series of intermediate sheets c of any desired number. 55 Each of these sheets is substantially con-

terminous with the margins of the cover and all are secured thereto by a line of stitches d which extends through the back or on the folding line of the cover. The sheet b 60 forms the first of the account pages of the book and is provided along one of its side margins with a space a' , in which the name of the depositor will be written by the teller when issuing the book and with an identifying number a^2 adjacent the same margin. Beneath the space a' , there is printed the caption a^3 , usually containing the name of the bank issuing the book and a subjoined date column a^4 , an interest column a^5 , withdrawal column a^6 , a deposit column a^7 , and a balance column a^8 , with cross rulings for consecutive entries of all of the transactions. The columns and cross rulings are continued from the inner margin of the title 75 page across the first page formed by one of the intermediate sheets c . Each of the leaves of the intermediate sheets is provided with a line of perforations c' substantially parallel to its outer side margin so that the 80 portion or slip c^2 of each leaf which overlies the name space a' and number space a^2 , when the book is closed, may be torn off as the successive pages are filled with entries. The columnar indications a^4 , a^5 , a^6 , a^7 and a^8 85 are repeated on the outer left hand margin of each of the intermediate pages, so that as the strips c^2 of each leaf is removed, they will be visible under the name of the depositor and for convenience in carrying the 90 account forward from the preceding pages of the book.

In practice, it is customary to number the 95 pages consecutively, as at a^9 , so that the removal of any of the leaves may be detected. The line of perforations c' makes it possible to remove the marginal strip c^2 when the right-hand page formed by an intermediate leaf has been filled with entries. The strip c^2 is utilized for advertising material or the like. 100

In use the name of the depositor is entered in the space a' when the book is issued. After the title page of sheet b and the opposite page formed by the first of the intermediate sheets c has been filled, the teller will tear off the strip c^2 of the first of the intermediate leaves, so that when it is turned over, the title page, the name of the depositor, and the number of the account, will be 105 visible, while the next two succeeding pages of the intermediate leaves are being filled 110

with entries. The removal of this strip makes it possible for the teller to read the name of the depositor and the number of the book while continuing the entries on the last mentioned pages until the last of them has been filled. In making the first entry on the succeeding page of one of the intermediate sheets c , he will tear off the slip c^2 , so that while the two next succeeding pages are being filled with entries, the teller can observe the name of the depositor and the number of the account. As the result of tearing off the marginal slips c^2 , the opening of the book at the page where the last entry occurs will be facilitated, because the teller can place his thumb over the remaining marginal portions c^2 of the untorn leaves and conveniently slip it into position to open the book at the page where the last entry occurs, thus greatly facilitating the teller's work.

The invention exemplifies a pass-book, particularly adapted for savings accounts in which the expense incident to the manufacture of books, composed of intermediate leaves which are shorter than the leaf containing the name of the depositor and caption, will be saved, thus materially reducing the cost of these books. It also exemplifies a book which facilitates the opening of the book by the teller or depositor at the page containing the last entry and usually showing the balance in the account. It also exemplifies a book for this purpose in which the marginal slips which are torn off are utilized to bring advertising or other matter to the attention of the depositor.

In practice, additional sheets having their margins conforming to the margin of the cover may be used between the sheet b and the cover for informative matter concerning the bank, and it is to be understood that these may be used, if desired, but that they do not form any part of the present invention.

The invention is not to be understood as restricted to the details set forth, since these

may be modified within the scope of the appended claims, without departing from the spirit and scope of the invention.

Having thus described the invention, what I claim as new and desire to secure by Letters Patent, is:

1. A pass-book for banks comprising a cover and a series of sheets with conterminous edges fixedly secured in the cover, one of the sheets being provided on one of its faces with appropriately designated space for the insertion of a name along and across one of its side margins, the leaves following the name-leaf being each provided with a line of perforations substantially parallel to and adjacent its side edge, extending substantially from the top to the bottom edges and rendering the portion thereof which laps said name-space removable, so that the name will be exposed when the strip is removed, the successive sheets having thereon columnar indications for the consecutive entries of an account.

2. A pass-book for banks comprising a cover and a series of sheets with conterminous edges secured along a medial line to the cover to form permanently connected leaves, one of the sheets being provided on one of its faces with appropriately designated space for the insertion of a name along and across one of the side margins of one of its leaves, the leaves following the name sheet being each provided with a line of perforations substantially parallel to and adjacent its side edge extending substantially from the top to the bottom edges and rendering the portion thereof which laps said name-space removable, so that the name will be exposed when the strip is removed, the successive leaves having thereon columnar indications for consecutive entries of an account.

Signed at Chicago, Illinois, this 21st day of May, 1927.

ALFRED GEORGE PILBROW.
